In Germany August 5, 1935

4 Claims. (Cl. 103—42)

Our invention relates to improvements in apparatus for feeding fuel to internal combustion engines, and more particularly in apparatus for feeding fuel from the fuel tank or tanks to the carburetor or injection pump of the engine. While the apparatus is valuable in connection with internal combustion engines of any type, it is particularly useful in connection with air craft. Our invention consists in providing two pumps having separate suction conduits for supplying the fuel from the tank or tanks and a common pressure conduit for supplying the said fuel to the engine. Thus both pumps feed the fuel independently of each other, fuel being supplied also when one of the said suction conduits is injured or one of the tanks is emptied, or if one of the suction conduits does not receive fuel from the tank by reason of the tank being inclined. Each pump is constructed for feeding an amount of fuel which is in excess of the highest demand of the engine, and a regulating device is provided for returning the excess of fuel from the pressure conduit to the suction conduits, the said fuel being returned into both suction conduits, so that in any case both pumps have a supply of fuel, even if only one of them receives fuel from its tank. This is important because thereby injury to the pump running idle is prevented.

For regulating the black flow of the fuel from the pressure conduit to the suction conduits a spring pressed regulating piston is provided in a regulating cylinder which is connected at one end of the piston with the pressure conduit, and which has return conduits or slots for the fuel provided in the cylindrical wall at diametrically opposite sides of the cylinder, so that the regulating piston is held in equilibrium within the cylinder and is not pressed to the wall thereof by the vacuum within one of the suction conduits. The regulating apparatus may be used in connection with pumps of any type. But it is preferred to provide pumps of the type in which the fuel is supplied by means of a pair of interengaging gear wheels rotating in a cylindrical casing and connected at one side of the pair of gear wheels with the suction conduit and at its opposite side with a pressure conduit. Preferably the said pumps are combined within one casing, corresponding gear wheels of the said pairs being mounted respectively on the same axis. In such pumps for feeding gasoline the clearance between the gear wheels and the adjacent sleeves and walls of the casing must be reduced as far as possible, in order to insure a sufficient vacuum and high efficiency. In pumps such as are now in use the

gear wheels are fixed to the shafts and the sleeves in which the shafts are rotatable in bushings fixed to the casing. Thereby the manufacture of the pumps with a small clearance is made difficult.

According to the invention pumps of the type referred to are used in which the gear wheels and the bushings have equal diameters. Pumps of this type are known. But as distinguished from such known pumps the gear wheels and the bushings are mounted so as to be floating in axial direction and so that the gear wheels and the bushings may set themselves into the positions which best answer the requirements of service.

For the purpose of explaining the invention an example embodying the same has been shown in the accompanying drawings in which the same reference characters have been used in all the views to indicate corresponding parts.

In said drawings:

Fig. 1 is a sectional elevation of the pump taken on the line 1—1 of Fig. 4.

Fig. 2 is a detail sectional view taken on the line 2—2 of Fig. 1.

Fig. 3 is a plan view partly in section taken on the line 3—3 of Fig. 1, and

Fig. 4 is a sectional view taken on the line 4—4 of Fig. 1.

In the example shown in the figures feed pumps of the type comprising pairs of interengaging gear wheels are provided, and the said pairs of gear wheels 2, 3 and 8, 9 are mounted within the same casing consisting of a cylindrical portion 11 and heads 32. The cylinder chamber is double and takes the form of two parallel and overlapping cylindrical spaces, as will be perceived on considering particularly Fig. 4 of the drawings. The suction conduits 23 and 24 of each pump are connected by means of pipes to the fuel tank or tanks, while the pressure conduits are connected through a passage 17 to a common tubular portion 16 of the casing of the pump, and the said tubular portion is connected through a pressure pipe with the carburetor or fuel injection pump of the internal combustion engine. The gear wheels 2 and 3 are mounted on a driving shaft 1 and they are connected therewith by means of keys 38 permitting axial play of the gear wheels on the shaft. The said driving shaft is mounted in bushings 4, 5, and 6, the bushing 4 being located between the gear wheels 2 and 3. The outwardly projecting end of the driving shaft is passed through a stuffing gland 7. The gear wheels 8 and 9 are loosely mounted on a shaft 10. In a modification the said gear wheels are

keyed to the said shaft, and the shaft is rotatably mounted in bushings 11, 12, and 13. In both cases the gear wheels are longitudinally shiftable on the shaft 10. In other modifications only the gear 5 wheels and the bushings 4 and 12, or all the bushings 5, 6, 11, and 13 and the gear wheels are axially shiftable. The end faces of the bushings 5 and 6 are flush with the end faces of the cylindrical casing 31, and accordingly the heads 32 10 have plane inner faces.

The diameters of the bushings and gear wheels are alike. One set of bushings, viz., the bushings 11, 12, and 13 are perfectly cylindrical, while the corresponding bushings 4, 5, and 6 are formed 15 with cut-out portions accommodating the bushings 11, 12, and 13. The bushings 11, 12, and 13 must be fixed as against rotary movement, while rotary movement of the bushings 4, 5, and 6 is prevented by the cut-out portions being engaged 20 by the bushings 11, 12, and 13, so that additional means for preventing rotary movement of the bushings 4, 5, and 6 may be dispensed with. As appears from Figs. 1 and 2 rotary movement of the bushing 12 is prevented by means of a screw 25 14 engaging in a slot 15 made in the bushing and permitting axial displacement thereof. Similar locking means are provided in connection with the bushings 11 and 13. The bushings form within the cylindrical spaces chambers within 30 which the gear-wheels rotate.

The excess of fuel fed by the pump or pumps is returned to both suction conduits through passages 21 and 22, and the back flow is controlled by means of a regulating device shown in Figs. 3 and 35 4. The tubular portion 16 providing the common pressure conduit of both pumps is connected through a branch conduit 17 with a regulating cylinder 18 in which a regulating plunger 19 is located, the said plunger being acted upon by a 40 spring 20 tending to shift the same to the right in Fig. 4 and into position for closing the conduits 21 and 22. The tension of the spring may be regulated by a screw 33. The bores through which the conduits 21 and 22 are connected with the 45 cylinder 18 are located at diametrically opposite parts of the said cylinder. At the rear or left hand side of the piston 19 the cylinder 18 is connected through a passage 25 either with the outer air or, where compressed air is supplied to 50 the engine, with the said supply of compressed air. Thus where compressed air is supplied to the engine the pressure of the fuel is always increased in the same degree as the pressure of the air supplied by the compressor to the engine. In

a modification the pressure of the said air is transmitted to the piston through the intermediary of an elastic diaphragm.

We claim:

1. An apparatus for feeding fuel to internal combustion engines, comprising two pumps having their suction passages adapted to be connected to the supply of fuel and having a common pressure conduit for the supply of fuel to the internal combustion engine, and a regulating device connected with said pressure conduit and with both suction passages and constructed for returning excess of fuel to both suction passages.

2. An apparatus as claimed in claim 1, in which the said regulating device comprises a cylinder 1 having a controlling member movably mounted therein, the said cylinder being connected at one side of the controlling member with the said pressure passage, the cylinder being provided in its walls with diametrically opposite bores communicating severally with the said suction passages, the said controlling member being movable in response to pressure in said pressure passage from a position of closure with respect to said bores.

3. An apparatus as claimed in claim 1, in which the regulating device comprises a cylinder having a plunger reciprocating therein, said cylinder being connected at one side with said pressure conduit and with said suction passages, the ports 3 establishing connection with the suction passages being made through the wall of said cylinder and at diametrically opposite parts thereof, and a spring acting on said plunger and tending 4 to shift the same in opposition to the pressure acting thereon and into position for closing said ports.

4. An apparatus for feeding fuel to internal combustion engines, comprising two pumps having their suction passages adapted to be connected to the supply of fuel and having a common pressure conduit for conveying fuel to the engine, and a regulating device including a plunger adapted to be subjected on one side to the pressure in the said pressure conduit and on the other side to the pressure of an air supply, and return passages from the pressure conduit to the suction passages of the two pumps, said plunger normally closing said passages and movable from its position of closure in response to excess pressure in 5 the pressure conduit.
